UNITED STATES PATENT OFFICE.

EDWIN S. DECKER, OF MALDEN, MASSACHUSETTS, ASSIGNOR TO GIBBY FOUNDRY COMPANY, OF BOSTON, MASSACHUSETTS, A CORPORATION OF MASSACHUSETTS.

HAND STOKER.

Application filed June 9, 1922. Serial No. 567,132.

To all whom it may concern:

Be it known that I, EDWIN S. DECKER, a subject of the King of Great Britain, and a resident of Malden, in the county of 5 Middlesex and State of Massachusetts, have invented an Improvement in Hand Stokers, of which the following description, in connection with the accompanying drawings, is a specification, like characters on the 10 drawings representing like parts.

The present invention relates to furnaces, stoves and the like heating devices wherein combustion takes place upon a grated fuel surface and aims to provide novel and improved 15 stoker bars and grate surfaces therefor. The invention will best be understood from a description of one selected embodiment thereof, reference being had to the accompanying drawings illustrating the 20 same, and wherein,—

Fig. 1 is a longitudinal section through a furnace showing the stoker in side elevation;

Fig. 2 is a detail top view of the lower 25 end of the stoker and portions of the adjacent furnace walls showing the cleaning bar and lowermost stoker bar in each unit, two such units being indicated in the present embodiment;

Figs. 3 and 4, detail perspective top views 30 of the stoker bar frame and the grate surface therefor, respectively;

Fig. 5, a detail top plan view of the stoker bar assembly;

Fig. 6, a front elevation of the same;

Fig. 7, a section on the line 7—7 of Fig. 6, 35 showing an interior view of one end of the stoker bar; and

Fig. 8, a detail longitudinal section of the 40 cleaning bar.

Referring to the drawings, the furnace herein shown and illustrating a selected embodiment of my invention operatively mounted therein, is of the hand stoking type and comprises a front wall 9, adjacent which 45 one end of the stoker is supported, a bridge wall 10, on which the rear end of the stoker is supported, opposite side walls 11, and an ash pit 12 arranged under the stoker, the front wall of the furnace being provided 50 with a suitable fuel opening 13 for each stoker unit, a separate opening 14 at a somewhat lower elevation for the passage of the stoker bar control rods, and a horizontal casting or dead plate 15 seated at 55 the bottom of the fuel opening 13.

As herein shown, the main frame of the stoker comprises three stringers 16 arranged in spaced parallel relation and adapted to support two separate stoker units, as shown in Fig. 2, two of these stringers being arranged near corresponding side walls of the furnace and the remaining stringer midway between the other two. The construction thus provides for two inclined stoker units, each of which is independent of the other 60 in construction and operation. It will be understood, however, that by the provision of additional stringers the fuel surface may be made up of as many stoker units as desired. 65

Each stringer is formed at its front end with a horizontal portion 17 providing a support for a coking plate 115 and is suitably recessed on its lower face to receive a supporting cross-rail 117 extended between 70 the side walls of the furnace, the lower end of the stringer being movably supported in a bearing box 18 built into the bridge wall and having an inclined bearing surface. 75

Each stoker unit comprises a plurality of 80 stoker bars 19 transversely arranged on the stringers and in parallel relation to each other, and a cleaning bar 20 adjacent the lowermost stoker bar at the inner end of the stoker. The construction of these stoker bars most clearly appears in the detail views 85 shown in Figs. 3 to 7, inclusive, while the cleaning bar is best shown in Fig. 2. Each stoker bar comprises a rocking frame and a unitary grate portion removably seated in 90 the frame, being without locking connection therewith and free to be moved into and out of operative position on the frame. The frame includes end plates 21, 21, and a curved shield portion 22 on the front side 95 connecting the end plates and preferably integral therewith. This shield is provided with a number of spaced apertures affording air passages 23, 23, etc., arranged in rows 100 extending the length of the shield intermediate its top and bottom edges, while a separate series of recesses 24, also designed to serve as air passages, is provided on the top edge of the shield. To prevent warping 105 of the shield when heated and consequent drawing of the end plates, its walls are suitably corrugated in the direction of its width. Each end plate 21 is provided with an integral trunnion 25 adapted to fit loosely in a suitable diagonal recess or slot 26 110

provided in the top edge of each of the stringers.

The stoker bars, herein shown as eight in number, are arranged to operate in separate series or groups, preferably in two groups of four successive bars each, the bars of each group being connected up by separate underlying actuating bars 27, the actuating bar of one group being arranged on one side of the unit while the corresponding actuating bar of the other group lies on the opposite side of the unit. Each of these actuating bars is connected to each individual stoker bar of the corresponding group by means of a curved lug 28 detachably secured by bolts 29 to one end of the shield 22 and provided with a depending bifurcated portion 30 which is arranged to straddle the actuating bar, being movably secured thereto by a removable hinge pin 31 which is passed through eyes 32 in the bifurcated portion and a suitable registering aperture in the actuating bar. Thus there is no interference between the actuating bars of the separate groups of stoker bars. Each group of stoker bars is controlled by a separate rod 33, connected to the actuating bar of that group and extending forward through the opening 14 in the front wall of the furnace to a lever 34 exteriorly mounted upon a bracket 35. Each lever is pivoted to be moved toward and away from the furnace wall for rocking the stoker bars by means of a detachable hand bar 36.

The grate portion of each stoker bar forms one continuous open structure extending between opposite end-plates 21 of the frame and constitutes the entire fuel supporting surface therebetween. In the present embodiment this grate surface is made up of a succession of diagonally arranged bars 37 connecting the front and rear side portions 38, 39. Each of these bars is constructed with corrugated inclined sides (see Figs. 2, 4, 5 and 7) to facilitate the necessary expansion and contraction of the metal without causing their distortion or the warping of the side portions, which are also corrugated for the same purpose. The side portions connect the end portions 40, 41, and are preferably formed integral therewith, the front side portion 38 being extended downward to movably engage the top edge of the shield 22 which is suitably cut away for the purpose and forms a supporting ledge therefor. Endwise movement of the grate portion during stoking or rocking operations is obviated by means of a pointed extension 42 provided centrally on the lower edge of the front side portion and adapted to register with a correspondingly shaped recess 43 provided on the shield. As clearly appears in Fig. 7, the contour of the front side portion conforms to the arc of the shield and serves as an upward extension thereof.

The rear side portion 39 is arranged in alignment with the trunnions 25, bridging the end portions, and is preferably deepened centrally. Each of the end portions is arranged to seat upon a horizontal ledge 44 formed on the inner face of the end plates 21 of the frame, which are reduced in thickness above this point. Each of said end portions is provided on its lower edge with a pair of depending retaining lugs 45, 46, which extend well down toward the lower margin of the corresponding end plate 21, being adapted to fit loosely into suitably shaped guide ways 47, 48, provided for their reception on the inner face of the end plate, the object of these lugs being to prevent displacement of the grate portion in either lateral direction during oscillations of the stoker bars. A suitable transverse opening 49, affording an air cooling passage and an outlet for any fine ash tending to collect on the shield at this point, is provided at the bottom of the forward guide way 47.

Each of the end portions 40, 41, is provided centrally on its outer face with a lateral extension or key 50 adapted to extend into a guide way 51 of somewhat greater depth provided on the inner face of the corresponding end plate 21 of the stoker bar frame to facilitate proper assembling of the grate portion in its frame and to prevent lateral displacement of the grate. As clearly shown in Figs. 5 and 6, the space between the end plates of the frame exceeds the lengthwise dimensions of the grate portion at all points sufficiently to insure ample allowance for endwise expansion of the grate portion without binding when heated.

The cleaning bar is arranged at the lower end of the stoker, extending from the lowermost stoker bar to the bridge wall, and comprises a frame of open structure in which is mounted a grate surface composed of a plurality of detachable sections 60. The frame portion comprises end plates 61, 61 connected at their front ends by an integrally formed downwardly curved perforate shield 62, the end plates being provided with aligned trunnions 63 which set into suitable recesses 64 provided in the top edge of the stringers 16 and as nearly as possible in line with the center of gravity of the cleaning bar so that the latter may be easily rocked or tilted downward at its rear or lower end by means of a rod 65 extending under the stoker and controlled from the front end of the furnace. This control rod 65 is pivotally connected at its rear end to a lug 66, which is similar to the lugs 28 of the stoker bars and secured by similar means centrally to the shield 62, the front end of the rod being extended forward through the opening 14 in the front wall of the furnace. The end plates 61 are connected at their lower extremities by an integral transverse bar 67,

which forms a support for the grate sections 60.

The grate surface of the cleaning bar is arranged in a plane offset from and below that of the grate surface of the stoker bars, each of the grate sections 60 having a downwardly curved portion at its front end extending from the level of the main portion of the stoker to a point approximately in the line of the axis of the trunnions 63, beyond which the remaining grate surface is flat. The grate sections are arranged in parallel and extend from front to rear of the cleaning bar, resting at their forward ends upon the top edge of the shield 62 and at their opposite ends upon the transverse portion 67, the forward ends being projected slightly beyond the arc of the shield to form a lip 68 overlying the rear edge of the adjacent stoker bar and designed to prevent downward displacement of fuel through the opening which would otherwise occur between the bars when the stoker bar is being rocked. The cleaning bar is provided with a plurality of air cooling passages distributed over its surface and consisting of a series of lateral recesses 69 on both margins of each grate section, the recesses of one section being arranged opposite the recesses of the adjacent section. Each of the grate sections is reinforced lengthwise by an integral perforate web 70 extending centrally along its bottom, the several sections being held against upward displacement by a transversely arranged removable rod 71 supported at its extremities in suitable openings provided in the end plates 61 and extending through aligned transverse openings in the webs of the grate sections.

In operating the device herein described, when it is necessary to shake the stoker to move the fuel toward the cleaning bar and remove any ashes that may fall through the stoker bars, the lower series of connected stoker bars is first rocked by manipulating the corresponding control rod, thereby projecting onto the cleaning grate ash and clinkers from the lowest stoker bar, while the partially or nearly consumed fuel of the remaining bars of this series is advanced to new position for the final stages of combustion. In like manner the upper series of stoker bars is then rocked, causing fresh fuel to be advanced from the coking plate and completing the gradual displacement rearward of the entire fuel bed. As the stoker bars are rocked their grate surfaces are raised above the stoker surface at such an angle that the entire overlying portion of the fuel bed is agitated and pushed onward, downward displacement of the fuel into the ash pit being effectually prevented by the curved shield on the front edge of each bar which closes the gap otherwise occurring between adjacent stoker bars. Each of these

shields forms a curvature designed to maintain at all times substantially uniform proximity to the adjacent stoker bar, the depth of the shield being equivalent to the extent of movement of the grated surface at its front edge. The same may be said of the shield of the cleaning bar which performs a like function. During oscillation of the stoker bars air is admitted to the fuel bed through the openings in the shield, which is thereby kept from being overheated while in direct contact with the fire.

To repair the grate surfaces of stokers of this class it is usually necessary on account of the locking connections of the several parts to remove the entire stoker bar from its setting on the stringers. This entails drawing the fire from the whole or a large portion of the stoker to permit detachment of the defective stoker bar from its actuating bar. In its economic aspects this necessity in the ordinary hand-stoker, often involving large commercial loss, is of much importance. In the present device this objection is reduced to a minimum and the operation of replacing the grate surface greatly simplified and expedited. This result is accomplished by the provision of a removable grate surface forming a complete and separate unit which has no positive locking connection whatever with its setting. Its detachment from the frame or remaining portion of the shaker bar may be readily accomplished by the mere operation of lifting it out of the frame, whether the furnace be in a heated or cold state, the preliminary clearing of the individual stoker bar only being required. Outward displacement of the grate portion from the frame during the shaking operation is prevented by the depending lugs 45, 46, arranged at each end, which then impinge upon the adjacent sides of their respective guide ways 47, 48, the length of the lugs being sufficiently extended to effect this result.

While the separate series of shaker bars are usually operated successively, they may, if desired, be operated simultaneously, in which event the shield portion of each bar will prevent fuel from falling between adjacent bars. The cleaning grate may be rocked whenever sufficient material is accumulated thereon to require removal. During oscillation of the cleaning grate the shield portion thereof operates to prevent loss of fuel in the same manner as the shields on the stoker bars. The weight of the cleaning grate is so distributed that it may be rocked easily, while its formation and position tend to distribute the load evenly over its surface.

It will be understood that the present invention is not intended to be restricted to the particular embodiment herein shown and that the same is equally applicable to other

4
types of furnaces, obvious modifications being made therein without departing from the principle of the invention.

I claim as my invention:

- 5 1. In a stoker bar, in combination, a frame comprising end portions and a member connecting the end portions and forming a shield, and a freely removable grate portion in one piece constituting the entire 10 fuel supporting surface intermediate the end portions and receiving support directly therefrom.
- 15 2. In a rocking stoker bar, in combination, a frame comprising end portions and a member connecting the end portions and forming a shield adapted to swing above the surface of the stoker when the bar is tipped, and a freely removable grate portion in one piece overlying the shield and 20 receiving support from said end portions.
- 25 3. In a stoker bar, in combination, a trilateral receiving frame having end portions and a member connecting the end portions on one side of the bar and forming a shield, a freely removable grate portion in one piece overlying the shield and receiving support from said end portions, and non-locking retaining means, for said 30 grate portion.
- 35 4. In a rocking stoker bar, in combination a frame having end portions and a member connecting the end portions, and forming a shield on the front side of the bar adapted to extend above the surface of the stoker when the bar is tipped, a unitary grate portion receiving support from said end portions and free to be moved into and out of operative position, and non-locking retaining means, including means provided on 40 the grate portion cooperating with means provided on said end portions for preventing displacement of the grate portion when the stoker bar is tipped.
- 45 5. In a stoker, a plurality of rocking stoker bars each comprising, in combination, a frame having end portions and a member connecting the end portions and forming a curved shield on the front side of the bar adapted to extend above the surface 50 of the stoker when the bar is rocked; a freely removable grate portion in one piece receiving support from said end portions and covering the shield, non-locking retaining means including dependent members provided on said grate portion and cooperative receiving means provided on said end portions of the frame for preventing displacement of the grate portion when the stoker 55

bar is tipped, and means for rocking the stoker bars collectively.

6. In a rocking stoker bar, in combination, a frame having end portions each provided on its inner face with a vertically arranged channel open at both ends, a member connecting the end portions and forming a shield extending above the surface of the stoker when the bar is tipped, and a freely removable unitary grate portion mounted in the frame and receiving support from said end portions, said grate portion having depending retaining members at its ends nearly equal in length to the depth of said end members and adapted to extend into said channels in the frame.

7. In a stoker, a rocking stoker bar, comprising in combination, a frame and a freely removable grate portion mounted in the frame, said frame having end portions and a member connecting the end portions and forming a curved shield adapted to swing above the upper face of the stoker when the bar is tipped, said shield being corrugated to prevent warping from expansion.

8. In a stoker, a rocking stoker bar comprising, in combination, a frame having end portions and a member connecting the end portions on the front side of the bar, and a grate portion free to be moved into and out of position on the frame and arranged to lap onto said end-portion connecting member, said grate portion forming a guard covering said end-portion connecting member and cooperating therewith to provide a shield on the front side of the bar adapted to swing above the upper face of the stoker when the bar is tipped.

9. In a stoker, in combination, a series of rocking stoker bars each having a grate receiving portion of open structure comprising end members and a member connecting the end members on the front side of the bar, a unitary grate portion free to be inserted into and withdrawn from the frame and receiving support from said end members, said grate portion being adapted to cover said side member of the frame and cooperating therewith to form a shield extending above the upper surface of the stoker when the stoker bar is rocked, trunnions eccentrically mounted on said end members of the frame, supporting means therefor, and means for rocking the stoker bar.

In testimony whereof, I have signed my name to this specification.

EDWIN S. DECKER.
